WALTER S. MCKEE, OF CHICAGO, ILLINOIS, ASSIGNOR TO EDGAR ALLEN AMERICAN MANGANESE STEEL COMPANY, OF AUGUSTA, MAINE, A CORPORATION OF MAINE.

RAILROAD-CROSSING.

1,152,032.

Specification of Letters Patent. Patented Aug. 31, 1915.

Application filed February 10, 1915. Serial No. 7,240.

To all whom it may concern:

Be it known that I, WALTER S. MCKEE, a citizen of the United States, and a resident of Chicago, in the county of Cook and State of Illinois, have made and invented 5 certain new and useful Improvements in Railroad-Crossings, of which the following is a specification.

This invention relates to railroad crossings, and more particularly to the construction of the intersections which form the same.

The present invention contemplates a structure of such design and arrangement 15 that an increased degree of safety shall be attained by providing a certain amount of flexibility in the crossing, allowing it to flex or bend slightly with the give of the foundation or road-bed, and thus eliminate danger 20 of breakage occasioned by the enormous strains imposed upon all crossings, particularly those located in main lines where heavy locomotives are used and where high rates of speed are maintained.

25 A further object is to provide a crossing intersection which includes a base plate to which are separately secured the four projecting rail pieces. The formation of the cross-rail member of separate and independent pieces prevents the strains from being communicated from one to the other, as 30 is the case in an integral cross-rail member, the strains being exceptionally high when subjected to the enormous weight of present 35 day rolling stock.

A further object is to provide a built-up crossing intersection wherein the several pieces, which project radially from the base plate, are formed as separate members, and 40 independently or separately bolted thereto, and between which members are provided reinforcing arms or braces, the resulting intersection being sufficiently rigid for the proper support of the traffic, at the same 45 time sufficiently flexible to allow a slight articulation between the various parts without damage to the crossing, and eliminating all danger of breakage at the point of junction of the rail members. At least eighty 50 per cent. of the failures of solid manganese steel crossings are directly traceable to the making of same in but two pieces or castings, the result being to provide an intersection having too great a degree of rigidity.

55 A further object is to provide a crossing

intersection with separate rail pieces whereby the loss involved in the breaking of one of the projecting arms of the cross-rails involves only the replacement of a single rail piece weighing but a few pounds, rather than the replacement of one or two entire cross-rail members weighing, in some instances, as high as twenty-five hundred pounds.

Other objects will appear as the description proceeds, wherein it is to be understood that changes in the precise embodiment of the invention can be made within the scope of what is claimed, without departing from the spirit of the invention.

The preferred embodiment of my invention is disclosed in the accompanying drawings, wherein:—

Figure 1 is a view in plan of two of the intersections which go to make up a complete crossing, the intersections embodying the characteristic features of my invention; Fig. 2 is an enlarged view in plan of a crossing intersection with two of the rail pieces detached from the base plate; Fig. 3 is a sectional view taken on the line 3—3 of Fig. 2; Fig. 4 is a view in section taken on the line 4—4 of Fig. 1; Fig. 5 is a view in section taken on the line 5—5 of Fig. 1; Fig. 6 is a view in plan of a somewhat modified form 75 of base plate; Fig. 7 is a view in end elevation thereof; Fig. 8 is a view in section similar to Fig. 3, and disclosing the form of rail member utilized in connection with the modified base plate illustrated in Figs. 6 and 80 7; Fig. 9 is a view in section of a somewhat further modified form of base plate and rail member; Fig. 10 is a view in section of a somewhat further modification of the foregoing; Fig. 11 is a fragmental view in section taken on the line 11—11 of Fig. 8, disclosing the manner in which each rail piece 85 is held against shifting with relation to the base plate; Fig. 12 is a view in perspective of a somewhat modified form of base plate 90 100 wherein the upstanding ribs are connected, whereby additional strength is lent to the base plate; Fig. 13 is a fragmental view in top plan and partially in section of an intersection including the modified form of base 105 plate just mentioned and illustrating the manner in which the rail pieces are recessed or slotted for the reception of the continuous or connected ribs; Fig. 14 is a view in section taken on the line 14—14 of Fig. 13; 110

Fig. 15 is a view in perspective of the type of base plate used in the intersection disclosed in Figs. 1 to 5 inclusive; Fig. 16 is a view in perspective of the base plate as used 5 in the intersection disclosed in Fig. 9.

Referring to the drawings, wherein similar reference numerals designate corresponding parts throughout, each intersection includes a base plate 15 which is provided with 10 the four pairs of upstanding and integral ribs 16 which radiate from a common central portion and provide means for the securing of the rail member of the intersection to the base plate. A number of openings 17 extend through the base plate and are adapted to receive holding spikes therein whereby the base plate is rigidly anchored to a suitable foundation or support.

It has been found in practice that it is 20 absolutely essential that the rail member 18 which is mounted upon the base plate be capable of flexing to a certain extent, due primarily to the fact that as a large weight is applied to the rail member of the intersection, it is transmitted to the base plate, causing the same to bear down upon its foundation or support. In time, the foundation or support gives slightly under the load, 25 allowing the base plate to become depressed as the train passes thereover, and were the rail member not capable of flexing or bending at its center, the forces or weight brought to bear upon the same will not be transmitted to, and borne by, the foundation 30 or support, but will cause severe bending moments within the rail member, and this continuous bending up and down, in the case of an integral casting forming a half crossing previously referred to as the usual design 35 at present in use, oftentimes causes the fracture and breaking thereof. In order to allow the cross-rail member 18 to flex slightly and thus compensate for any give in the foundation, supporting the base plate, I form the rail member of the four separate and independent rail pieces 19-20-21-22, two of which, 19-20, being provided with the rail engageable ends 23, and the other two, 21-22, extending to, and 40 forming a part of, the adjacent intersections of the crossing. The rail pieces 19 and 21 include the wearing portions 24, and the guards 25, between which is defined a groove or runway 26 for the passage of the flange 45 of a wheel therethrough. The rail pieces 19 and 21 extend to the center of the base plate and abut so as to form a continuous rail. The ends of the rail pieces 19-21 are provided with the grooves 27, defining a runway 28 extending across the continuous rail defined by the pieces 19-21. A portion of the extremities of the guards 25 of the rail piece 19 and 21 are cut away as at 55 29, defining a recess into which the extremity of the rail piece 22 is adapted to

seat. The rail pieces 20-22 abut against the sides of the rail pieces 19-21 and include the wearing portions 30 and guards 31, between which extend the runways 32, the same being positioned in alignment with 70 the transverse runway 28 provided in the continuous rail 19-21.

The various rail pieces are cored, as illustrated by the dotted lines in Fig. 2, so that each rail piece is formed with the sides 75 34-36 which are spaced a distance from the outer edges of the rail piece, so as to define the supporting ledges 35-37. The upstanding ribs 15 of the base plate are arranged so as to embrace and contact with 80 the sides of the rail pieces and provide supports upon which the ledges 35-37 of the rail pieces are adapted to rest. A secure anchorage between the base plate and rail pieces is effected by providing the rail pieces 85 with a number of bosses 38, which extend between the spaced sides of the rail pieces and are provided with the bolt receiving openings 39. The bolt receiving openings 39 are formed as a continuation of similar 90 openings 33, which extend through the sides of the rail pieces, and the upstanding ribs of the base plate are also provided with a number of openings 39', adapted to register with the aforementioned openings and receive the anchoring bolts 40 therethrough.

Angle braces 41 extend between the adjacent ribs 16 of the base plate and are provided with the bolt receiving openings 42, through which the anchoring bolts 40 extend and by means of which the braces are securely held in place, so as to materially strengthen and reinforce the entire structures. The angle braces are of such height that they contact with the ledges 35-37 of 105 the rail pieces and aid in the support thereof. The built-up intersection as thus constituted may articulate or bend to such extent as to compensate for any depression of the base plate by the slight giving of the 110 foundation or road-bed which supports the same, as a heavy load passes thereover.

A somewhat different method of securing the various rail pieces to the base plate is 115 illustrated in Figs. 6 to 8 inclusive, wherein it will be observed that the base plate 15' is provided with four single upstanding ribs 43 and with four spaced abutment blocks 44 adjacent each of the single ribs 43. The rail pieces used in connection with this form of 120 base plate each include, as illustrated in Fig. 8, a wearing portion 45, a guard 46 and the spaced supporting sides 46a. The wearing portion and guards of the various rail pieces 125 are matched and arranged similar to those heretofore described, two of the rail pieces abutting end to end and the other of the two rail pieces contacting with the sides thereof. The rail pieces are U-shaped in cross-section, 130 as illustrated in Fig. 8 and are provided at

spaced intervals with the bosses 53, the ends of which terminate a distance from one side of the rail piece, so as to provide a space for the reception of the upstanding rib 43 of the base plate. The spaced sides and bosses of the rail pieces are provided with the openings 54 extending therethrough, which are adapted to align with the openings 54^a which are provided in the ribs of the base plate. 5
10 Suitable anchoring bolts 55 extend through the aligned openings and through corresponding openings 56 formed in the braces 57, and thus anchor the various parts in their assembled and intersection-forming relation. In 15 order to further strengthen and reinforce the anchorage between the rail pieces and the base plate, the sides of the rail pieces are provided at their lower extremities with the flanges 48 which are provided at spaced intervals with the notches 49, and into which the spaced abutment blocks 44 are adapted to seat. In this manner, the rail pieces are positively held against shifting with relation to the base plate and without in any way 20 25 hampering the slight articulation therebetween.

A somewhat different form of intersection, but embodying the same principles, is disclosed in Figs. 9 and 16, wherein it will be observed that the base plate 58 is provided with the four pairs of spaced upstanding ribs 59, the upper extremity of each pair being connected and reinforced by the top members 60. The top members are provided 30 35 with the concave outer surfaces corresponding to, and adapted to receive, the lower surfaces of the rail pieces thereagainst. The rail pieces are provided with the supporting sides 61—62, so spaced as to embrace 40 and contact with the external sides of the ribs 59 of the base plate, and are thus held against shifting thereby. The base plate is formed with openings between the upstanding ribs 59, so that the casting thereof may 45 be more easily accomplished and the space intermediate said ribs is provided at intervals with the bosses or lugs 63, through which extend the anchoring bolts 64, the same extending through aligned openings 65 50 formed in the sides of the rail piece and the ribs and bosses of the base plate. Reinforcing or bracing bars 65 are also included in this form of intersection and extend between the sides of adjacent rail pieces, receive 55 the anchoring bolts 64 therethrough, and materially increase the strength of the entire structure.

The somewhat further modification illustrated in Fig. 10 is similar to the intersection disclosed in Figs. 1 to 5 inclusive, with the exception that in the present instance, the upstanding ribs 67 of the base plate 66 are spaced closer together and fit between the confronting faces of the sides 68 of the rail pieces. The bosses 38' are formed integral

with and extend between, the ribs 67 of the base plate and prevent the bending of the ribs by the anchoring bolts 70 which extend through suitable openings 71, which are formed therein. The openings 71 extend 70 through the sides of the rail pieces, through the upstanding ribs of the base plate and through the bosses 38'. The angle braces 73, which extend between the sides of the adjacent rail pieces, are provided with aligned 75 and registering openings 72, through which the aforementioned anchoring bolts extend, whereby the entire structures are anchored together and materially reinforced.

From the foregoing, it will be apparent 80 that each rail member is rigidly secured to the base plate by a number of anchoring bolts, and the relative shifting of parts in a horizontal plane is prevented by the ribs of the base plate and the configuration of 85 the rail pieces, which are used therewith. The rail pieces being formed separately, may articulate to a slight extent, so that, although the foundation should give slightly under heavy loads, the base plate will also be 90 allowed to give slightly or be depressed, without undue strains being brought to bear upon the rail pieces, such as would occur at the center of the cross-rail member, were it cast in a single piece. 95

The supporting ribs, with which the base plate is provided, may be connected so as to radiate from a common central portion, as illustrated in the modified forms in Figs. 12 to 14 inclusive, wherein the base plate is materially strengthened and reinforced. In those instances wherein the various ribs of the base plate are connected, the rail pieces which go to make up the cross-rail member, are provided with suitable grooves, through 100 which the ribs of the base plate may extend. In the several views just mentioned, a form of construction similar to that disclosed in Figs. 6 to 8 inclusive is shown, wherein the upstanding ribs 43' are connected and the 110 rail piece 19' is provided with the grooves or recesses 74 extending thereacross and with the groove or recess 75 extending through the front wall thereof, thereby accommodating the connected upstanding ribs 115 43' of the base plate. The rail member 22' is provided with the recess or opening 76 in the front wall thereof, which is adapted to register with the recesses 74 in the member 19', and thus accommodate the continuous or connected ribs of the base plate. The arrangement of the remaining rail pieces is similar to the foregoing, they being provided with suitable recesses in their front walls for the accommodation of the ribs of 120 the base plate. The property of being able to give slightly with the giving of the roadbed is preserved in this latter mentioned form and all danger of breakage or fracture at the center of the cross-rail member 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

is eliminated, although the rail pieces 21 and 22 which extend between the adjacent intersections are each illustrated as being formed as a single casting, it will be understood that the same may be made of two or more sections secured together in any preferable manner, without departing from the spirit of the invention.

I claim—

10. 1. A crossing intersection comprising a base plate with upstanding ribs and a plurality of cast rail members each including a wearing portion and a guard, secured to said ribs.
15. 2. A crossing intersection comprising a base plate with upstanding ribs, abutting rail-forming members secured to said ribs, each rail-forming member including a wearing portion and guard with a runway therebetween, said wearing portion and guard provided with spaced sides resting upon said base plate.
20. 3. A crossing intersection comprising a base plate with upstanding ribs, a plurality of cast rail members, each including a wearing portion and a guard, said wearing portion and guard provided with downwardly extending sides resting upon said base plate and contacting with said upstanding ribs and secured thereto.
25. 4. A crossing intersection comprising a base plate with upstanding ribs arranged in pairs, a plurality of rail members including spaced sides, said sides contacting with the upstanding ribs of the base plate and secured thereto.
30. 5. A crossing intersection comprising a base plate with upstanding ribs arranged in pairs, a plurality of cast rail members each

including spaced sides contacting with the 40 said ribs, said ribs and sides provided with aligned openings, and holding bolts extending through said openings, holding the several parts in proper relation.

6. A crossing intersection comprising a 45 base plate with upstanding ribs arranged in pairs, and a plurality of cast rail members secured thereto, each including spaced sides contacting with said ribs and held against lateral shifting thereby.

7. A crossing intersection comprising a base plate with upstanding ribs arranged in pairs, a plurality of cast rail members secured thereto, each rail member including a 50 top and spaced sides, said sides spaced a 55 distance from the outer edges of said top defining supporting ledges, the sides of said rail members contacting with said upstanding ribs, and said ledges resting upon the tops of said ribs.

8. A crossing intersection comprising a base plate with upstanding ribs arranged in pairs, a plurality of rail members secured thereto and each including a wearing portion and a guard, said wearing portion and guard provided with downwardly projecting spaced sides contacting with the faces of said ribs and held against lateral shifting thereby, said wearing portion and guard resting upon the tops of said upstanding ribs.

Signed at Chicago, in the county of Cook and State of Illinois, this 8th February A. D. 1915.
